Primary Examiner—Lucy Lieberman*(74) Attorney, Agent, or Firm*—Oblon, Spivak, McClelland, Maier & Neustadt, L.L.P.(57) **CLAIM**

The ornamental design for a wristwatch, as shown and described.

DESCRIPTION

FIG. 1 is a front and right side perspective view of a wristwatch;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof; and,

FIG. 7 is a top plan view thereof.

The broken lines in the drawings depict environmental subject matter only and form no part of the claimed design.
